UNITED STATES PATENT OFFICE

AUGUST E. CARLBERG, OF WORCESTER, MASSACHUSETTS, ASSIGNOR TO STEVENS WALDEN, INCORPORATED, OF WORCESTER, MASSACHUSETTS, A CORPORATION OF MASSACHUSETTS

WRENCH

Application filed January 7, 1930. Serial No. 419,178.

This invention relates to that type of wrench in which two heads are pivotally connected with the handle on axes at right angles to the length of the handle.

5 The principal objects of the invention are to provide improved heads for the type of wrench shown and claimed in my prior patent, Reissue No. 16,354, issued June 16, 1925, on original Letters Patent No. 1,542,336; to 10 provide an improvement in which a larger number of tools will be made available for use in a single device and in fact, in its preferred form, it is provided with fifteen members adapted to fit different nuts, heads, 15 sockets, slots and the like and to provide a plug wrench having a number of individual members, each one being capable of being used at any desired angle and with full efficiency at all angles.

20 Other objects and advantages of the invention will appear hereinafter.

Reference is to be had to the accompanying drawings, in which

25 Fig. 1 is a side view of a complete wrench constructed in accordance with this invention;

Fig. 2 is a plan of the same;

Figs. 3 and 4 are sectional views on the lines 3—3 and 4—4 respectively of Fig. 2;

30 Fig. 5 is a side view of one end of the wrench handle or shank with the wrench head removed; and

Fig. 6 is a side view of one of the heads.

This invention is shown as applied to a 35 wrench handle or shank 10 in the form of a bar or wire, preferably straight from end to end, but having the two ends extending at right angles therefrom and constituting

40 studs 11 parallel with each other and perpendicular with the shank for receiving two wrench heads 12 and 13. The principle of this wrench is covered in my above mentioned reissue and the improvement consists in the heads.

45 Each of the heads 12 and 13, instead of being provided with two sockets as shown in said reissue, is provided with four members which can be in the form of sockets or plugs or both. The head 12 is shown as having four square plugs 14, 15, 16 and 17, all of

different sizes, and each adapted to enter a square hole. Three of these, namely 14, 16 and 17 are also provided with square sockets 18, also three different sizes. The fourth plug 15 is provided with a hexagon socket 19 and with a groove 20 extending entirely across it from side to side. The hexagon socket of course is for a hexagon nut or head and the groove is for a straight rib or projection.

55 It will be obvious that this head can be turned on its stud 11 to any desired angle with respect to the handle or shank 10 and that the desired socket or plug can be put into juxtaposition with the article to be turned. The handle extends from it in the proper direction for securing an effective leverage and can be turned up on the axis of the stud 11 to different angles for convenience and still will have considerable leverage for turning the desired element. It 60 will be seen that this head provides nine wrenches or tools.

65 The other head 13 is similarly provided with a series of four square plugs 22, 23, 24 and 25. In spite of the configuration of two of them, which will be described later, they all serve as square plugs for the same purposes as the plugs on the other head but are made of smaller sizes for an obvious purpose. In addition to the four plugs, two of them 70 are provided with diagonal projections 26 and 27 extending from corner to corner and constituting in effect screw-driver tips. This head therefore, as shown, presents six tools adapted to be used in six different kinds of places making fifteen in all.

75 It is believed that no wrench has ever been provided furnishing such a large number of separate tools or individual wrenches all capable of being used at any desired angle. The heads turn freely on their studs 11 and yet there is no tendency of the wrench to slip off or out of the article to which it is applied because when it is turned the turning motion is always about the axis of that article and there is really no force used in the ordinary application of the wrench which will have any important tendency to dislodge the plug or wrench socket or the like from the article.

to which it is applied. This is a very convenient tool to use and very inexpensive because so many tools are embodied in it.

In order to hold each head 12 and 13 in position on the stud 11 the stud is provided with a spring pressed round headed pin or ball 30 extending radially and projecting into a circumferential concave groove 31 in the inside of the head. This avoids the riveting over of the end of the stud 11 and holds the head against removal in an axial direction accidentally, although it can be removed by exerting enough force on it, because the groove has no square shoulder. This pin also exerts a little friction so the head will not spin on the stud and will be held with some degree of force in any position in which it may be placed, thus adding to the certainty of the operation and the efficiency of the 20 tool.

Although I have illustrated and described a single embodiment of the invention and shown a specific wrench in which fifteen different tools are embodied, I am aware of the 25 fact that the same principle can be carried out with the adoption of more or less tools and that other modifications can be made therein by any person skilled in the art without departing from the scope of the invention 30 as expressed in the claims. Therefore, I do not wish to be limited in these respects, but what I do claim is:—

1. As an article of manufacture, a wrench comprising a handle or shank having a stud 35 projecting at right angles from its end, a head rotatably mounted on the stud and having projections extending from the different sides thereof, said projections having a polygonal shape and being of different sizes to 40 constitute a plurality of different wrench plugs, certain of said plugs being provided with straight sided projections extending diagonally from corner to corner and constituting screw-driver tips, whereby those plugs 45 serve two different purposes.

2. As an article of manufacture, a wrench comprising a handle or shank having a stud projecting from its end, a head mounted on the stud and having a projection extending 50 from the side thereof, said projection having a polygonal shape, and being provided with a straight sided projection extending diagonally from corner to corner and constituting a screw-driver tip constituting part 55 of the plug.

In testimony whereof I have hereunto affixed my signature.

AUGUST E. CARLBERG.
